[57] CLAIM

The ornamental design for an ice tray, as shown.

DESCRIPTION

FIG. 1 is a top plan view of an ice tray showing my new design;

FIG. 2 is a side elevational view thereof, the opposite side being substantially a mirror image of the side shown herein;

FIG. 3 is a bottom plan view thereof;

FIG. 4 is an end elevational view thereof, the opposite end being substantially a mirror image of the end shown herein; and

FIG. 5 is an enlarged fragmentary sectional view thereof taken along line 5—5 of FIG. 2.

*Fig. 1.**Fig. 2.**Fig. 3.**Fig. 4.**Fig. 5.*
